DESIGN FOR AN ELECTRICAL HAWAIIAN GUITAR

Robert L. Miekley, Essington, Pa.

Application October 18, 1946, Serial No. 134,065

Term of patent 14 years

(Cl. D56—1)

To all whom it may concern:

Be it known that I, Robert L. Miekley, a citizen of the United States of America, residing at Essington, in the county of Delaware and State of Pennsylvania, have invented a new, original, and ornamental Design for an Electrical Hawaiian Guitar, of which the following is a specification, reference being had to the accompanying drawing, forming a part thereof.

The single figure of the drawing is a side perspective view of an electrical Hawaiian guitar, showing my new design.

The drawing has been shaded to show contrasting appearance.

I claim:

The ornamental design for an electrical Hawaiian guitar, as shown and described.

ROBERT L. MIEKLEY.
